(57) CLAIM

The ornamental design for the golf trunk organizer as shown and described.

DESCRIPTION

FIG. 1 is a top, front, left perspective view of a golf trunk organizer showing my new design;

FIG. 2 is a bottom, rear, right side perspective view thereof;

FIG. 3 is a top, rear, right side perspective view thereof;

FIG. 4 is a front view thereof;

FIG. 5 is a rear view thereof;

FIG. 6 is a left view thereof;

FIG. 7 is a right view thereof;

FIG. 8 is a top view thereof;

FIG. 9 is a bottom view thereof.

FIG. 10 is an enlarged view of the area '10' in FIG. 3;

FIG. 11 is a perspective view thereof, showing an open configuration of the golf trunk organizer; and,

FIG. 12 is a perspective reference view thereof, showing a usage state of the golf trunk organizer.

The broken lines in the figures depict portions of the golf trunk organizer that form no part of the claimed design. The zipper stitches in broken lines shown in the figures also form no part of the claimed design.

1 Claim, 12 Drawing Sheets
